UNITED STATES PATENT OFFICE.

HOWARD T. STROOP, AUGUST F. HAUSER, AND JULIUS HAMMER, OF PEORIA, ILLINOIS.

ROLLING TUB STAND.

Application filed November 22, 1923. Serial No. 676,234.

The present invention relates to rolling tub stands.

The object of our invention is in the provision of a collapsible stand having casters thereon enabling it to be moved about readily when in the upright position and also permitting movement when in the collapsed position.

Another object of our invention is in a provision of a collapsible metal stand member having roller portions fastened thereon in such a manner that movement of the stand is permitted either in the upright or collapsed position.

15 The present stand member was developed mainly for use in connection with the well known washing operation, wherein the movement of heavy water filled tubs is necessary in the various washing steps, including the 20 rinse operation, bluing etc.

Normally the housewife utilizes any sort of stand member to support the tubs adjacent the washing machine, but unless such member is provided with roller members, the 25 lifting of the heavy tub is still necessary.

The present stand, however, has for its object not only the ready movement of the heavy tub members from place to place but also the feature of collapsibility whereby it 30 may be collapsed substantially to the plane of the floor and removed to a space that the normally upright stand could not possibly fit into.

In order to provide not only a permanent 35 but a sufficiently strong stand to support the heavy water filled tubs, said stand is necessarily made of metal, thereby making the stand itself of considerable weight. For the further convenience of moving the stand, I 40 have fashioned it in such a manner as to be capable of being rolled even when in said collapsed position.

Fig. 1 is a side elevation of the stand in its upright position.

45 Fig. 2 is a side elevation showing it partially collapsed.

Fig. 3 is a side elevation showing the stand entirely collapsed.

Fig. 4 is a top plan view.

50 Fig. 5 is an end elevation of the stand as shown in Figure 3.

Fig. 6 is an enlarged detail of the hinge portions, and

55 Fig. 7 is an enlarged detail of one of the corners showing the manner of catching the foldable legs under the top.

Referring to the drawings, we have shown a skeleton top or platform having its edges formed of angle bars 10 and 11, connected at the corners in any convenient manner. 60

The cross bars 12 are securely attached as at 13 to the angles 11.

At 14 and 15 are shown two pairs of leg portions pivoted with respect to each other as at 16 to permit a folding relationship. 65

A cross bar 17 connects the lower ends of the pair of legs 15 and a similar bar 18 connects legs 14 at a similar point. Attached to lower ends of each of the leg portions are the offset brackets generally designated as 70 19. These brackets have a hub portion 20 connected to the ends of the legs and in the same plane thereof, said hubs being fastened thereto by means of the nuts 20^a, which also provide fastening means for the transverse 75 bars 17 and 18.

These brackets 19 have offset portions 22, which provide bearings for the conventional rolling casters 23.

Attention is drawn at this time to the off- 80 set mounting of the roller or caster members with relation to the leg portions.

The means for pivotally attaching the platform to the leg portions is provided in the following mechanism; a pair of pins 24 85 projecting outwardly from the upper ends of the legs 15, said pins engaging adjacent slots 25, formed in the side portions 10.

It will thus be seen that the stand is maintained in raised or extended position by the 90 downwardly extending flanges of the angles 11, against which the beveled upper ends of the legs abut. The purpose of the elongated slots 25 is to permit movement of pins 24 therein when the opposite edge of the platform is raised to disengage it from the 95 legs 14.

In Figure 7 the opposite side of the stand is shown or rather an enlarged detail of one corner, wherein a transverse bar 26 connects 100 the upper ends of the leg portions 14.

In Figure 1 the stand is shown in its upright position and adapted to be moved about with little effort even though supporting a heavy wash tub. 105

To collapse the stand it is merely necessary to raise the platform slightly at the opposite side from the hinge portion, whereby the leg portions will fold as shown in Figure 2, until finally the stand is in the collapsed 110 position shown in Figure 3.

In Figure 3 it may be seen that it is due

2
to the offset mounting of the roller members that the stand may be collapsed to take up so small a space and at the same time to be rolled around either by hand or by foot to any place desired.

What I claim is:

A device of the class described, comprising two cooperating collapsible frames, each formed of two legs pivoted together intermediate their ends, rollers on said legs adapted to support the device for rolling in collapsed and extended positions, a platform having two opposite edges, and downwardly

extending flanges at said edges adapted to engage the upper ends of said legs in abutting relation to thereby maintain the device in extended position, said platform being provided with two elongated slots adjacent one of said edges, two corresponding legs of said frames being pivoted to said platform by means of pins passing through said slots. 15

In testimony whereof we affix our signatures.

HOWARD T. STROOP.
